UNITED STATES PATENT OFFICE.

FREDERICK A. STEVENS AND JAMES W. WELSH, OF PROVIDENCE, RHODE ISLAND, AS
SIGNORS, BY MESNE ASSIGNMENTS, TO BAUSCH AND LOMB OPTICAL COMPANY,
OF ROCHESTER, NEW YORK, A CORPORATION OF NEW YORK.

OPHTHALMIC MOUNTING AND METHOD.

Application filed July 8, 1922. Serial No. 573,656.

The present invention relates to ophthalmic mountings and methods of making the same.

The chief object of the invention is to improve upon present-day methods of manufacturing endless non-metallic lens rims. Other objects will appear hereinafter.

In the accompanying drawings, Fig. 1 is a view of a lens rim constructed according to a preferred embodiment of the present invention; Fig. 2 is a detail of the same, partly in section; Figs. 3, 4, 5 and 6 are similar details of modifications; Fig. 7 is a section taken upon the line 7—7 of Fig. 6; Figs. 8, 9 and 10 are views similar to Fig. 2 of further modifications; and Fig. 11 is a section taken upon the line 11—11 of Fig. 10.

It has been the practice hitherto to manufacture endless lens rims of non-metallic material, like zylonite and the like, by dieing them out of sheet stock. This practice involves great waste, for the portions of the stock between the rims, and the circular disks cut from the centers of the rims, are scrapped.

There is hardly any waste involved in the use of the present invention. Not sheet stock, but preferably cylindrical rods of the non-metallic material are employed. There is a further saving in labor and materials thus effected in that it is not necessary to smooth or round off the edges of the rims, as is the case with die-cut stock. The rod is bent into the form of a ring 2, as shown in Fig. 1, and the ends 4 and 6 of the bent rod are joined together to form a continuous ring. The inner face of the ring is then grooved at 8 to provide the thus completed rim with a lens seat, or the rod may be initially grooved to start with, before it is bent into the ring form.

According to the preferred form of the present invention, shown in Figs. 1 and 2, the ends 4 and 6 of the rod are reduced in cross section at 10 and 12, the reduced ends are inserted into recesses 14 and 16 of a non-metallic ferrule 18, and the reduced ends are then cemented to the walls of the recesses. The ferrule 18 may conveniently be made from a short non-metallic rod of the same substance and cross-sectional diameter as the rod 2, though of smaller length, the recesses 14 and 16 being shaped to corre-

spond to the shape of the reduced ends 10 and 12. In the drawings, the shape is shown as conical. Of course, the ferrule 18 is bent to conform to the circumference of the completed rim. A rim so constructed has all the attributes of present-day rims of this character, except that it is very much cheaper.

The relative dimensions of the rods 2 and 18 may be reversed, as shown in Fig. 3. In this figure, the ends of the rod 18 are reduced in cross section, and these reduced ends fit into correspondingly shaped recesses provided in the ends of the rod 2.

The rims shown in Figs. 1, 2 and 3 are composed of two rods 2 and 18. A continuous rim may, however, be made from a single rod by recessing one end of the rod at 20, Fig. 4; reducing the cross section of the other end, as shown at 22, inserting the reduced end 22 in the recess 20, and cementing the reduced end to the walls of the recess.

The ferrule 18, Figs. 1 and 2, need not necessarily be of the same diameter as the rod 2. In Fig. 5 is shown a construction in which the ferrule 24 is of larger cross section. In that event, it will not be necessary to reduce the cross section of the ends 4 and 6 of the bent rod 2. The ends 4 and 6 may be inserted into cylindrical recesses 26 and 28 and suitably cemented in place.

The non-metallic rims are, of course, intended to be secured to a nose bridge or to be pivoted to spectacle temples, or both. This is ordinarily effected by means of metal clamps that are secured to the ends of the bridge or to which the temples are pivoted. The clamps will naturally be positioned so as to clamp the joined-together ends of the ring, thus hiding the joints at the ends of the bent rod 2. Such a clamp may, furthermore, if suitably constructed, itself act as the medium for joining the ends of the bent rod 2 together. One such construction is illustrated in Figs. 6 and 7. In these figures, the ends 4 and 6 of the bent rod 2 are simply juxtaposed together, though a layer of cement may, if desired, be placed at the dividing line between the ends 4 and 6. The ends 4 and 6 of the ring are provided with transverse corrugations 30, and the clamp 32 is similarly provided with trans-

verse corrugations 34, the corrugations provided upon the rod 2 to hold the parts together. Of course, the corrugations 30 might be provided upon the ferrule 18 or the ferrule 24.

Other methods of joining the ends of the ring 2 together with the aid of metal are illustrated in Figs. 8 to 11. According to the construction of Fig. 8, the ends 4 and 6 of the rod 2 are provided with transverse recesses 36 and 38, and aligned longitudinal recesses 40 and 42. The ends of a metal strip 44 are inserted through the transverse recesses 36 and 38 until the body of the strip 10 becomes seated in the aligned longitudinal recesses 40 and 42, and the tips 46 and 48 of the strip are clinched over against the rod 2, as shown.

A very effective construction is shown in 20 Figs. 9 to 11. The ends of the rod 2 are provided with aligned longitudinal, transversely corrugated recesses 50 and 52. These recesses may be on the outer face of the rim, Fig. 9, or the inner face, Figs. 10 and 11. A transversely corrugated metal clamp 56 is inserted into the aligned recesses 50 and 52 to hold the ends of the rod together. The corrugations dovetail into one another in the same manner as described 25 above in connection with the description of Fig. 6.

Many other modifications will occur to persons skilled in the art, and all such are intended to be embraced within the spirit 30 and scope of the appended claims.

What is claimed as new is:

1. The method of making an article of the class described that comprises bending a zylonite rod into the form of a ring, inserting 40 the ends of the rod in a zylonite ferrule, and cementing the ends of the rod to the ferrule to form a continuous ring.

2. The method of making an ophthalmic mounting that comprises bending a non-metallic rod into the form of a ring, inserting 45

the ends of the rod in a non-metallic ferrule, cementing the ends of the rod to the ferrule to form a continuous ring, and grooving the inner face of the ring and ferrule to provide it with a lens seat. 50

3. The method of making an article of the class described that comprises recessing an end of a zylonite rod, bending a second zylonite rod, reducing the cross section of one of the ends of the second rod so that the 55 said end may enter the recess in the first-named rod, inserting the reduced end in the recess, and integrally uniting the reduced end to the walls of the recess.

4. The method of making an ophthalmic 60 mounting that comprises recessing the ends of a short non-metallic rod, bending a second non-metallic rod of diameter equal to the diameter of the first-named rod into the form of a ring, reducing the cross section of 65 the ends of the second rod so that they may enter the recesses in the first-named rod, inserting the reduced ends in the recesses, cementing the reduced ends to the walls of the recesses to form a continuous ring, and 70 grooving the inner face of the ring to provide it with a lens seat.

5. An ophthalmic mounting comprising a non-metallic rod bent into the form of a ring, the ends of the rod being inserted in 75 a non-metallic ferrule and cemented to the ferrule to form a continuous ring, the mounting being provided with a lens-receiving groove.

6. The method of making an ophthalmic 80 mounting that comprises bending a zylonite member into the form of a ring, joining the ends of the member together with cement so as to form a continuous ring, and providing the inner face of the ring with a lens seat. 85

In testimony whereof, we have hereunto subscribed our names this 6th day of July, 1922.

FREDERICK A. STEVENS.
JAMES W. WELSH.
